US00D980688S

(12) **United States Design Patent** (10) **Patent No.:** **US D980,688 S**
(45) **Date of Patent:** **** Mar. 14, 2023**

(54) **PORTABLE TOOL**

(71) Applicant: **Ming Yang**, Calgary (CA)

(72) Inventor: **Ming Yang**, Calgary (CA)

(**) Term: **15 Years**

(21) Appl. No.: **29/786,240**

(22) Filed: **May 30, 2021**

(30) **Foreign Application Priority Data**

May 3, 2021 (CN) 202130263752.8

(51) **LOC (14) Cl.** **08-05**

(52) **U.S. Cl.** **D8/105**
USPC **D8/105**

(58) **Field of Classification Search**

USPC D8/14, 26, 34, 41, 55, 93, 98, 99, 104,
D8/105, 89; D21/532
CPC B25F 1/00; B25F 1/003; B25F 1/02; B25B
7/22

(57) **CLAIM**

The ornamental design for a portable tool, as shown and as described.

DESCRIPTION

FIG. 1 is a perspective view showing my new design.

FIG. 2 is a front view of FIG. 1.

FIG. 3 is a rear view of FIG. 1.

FIG. 4 is a left end view of FIG. 1.

FIG. 5 is a right end view of FIG. 1.

FIG. 6 is a top view of FIG. 1.

FIG. 7 is a bottom view of FIG. 1.

FIG. 8 is a perspective view showing my new design while the clamp head and the knife blade thereof are unfolded.

FIG. 9 is a front view of FIG. 8.

FIG. 10 is a rear view of FIG. 8.

FIG. 11 is a left end view of FIG. 8.

FIG. 12 is a right end view of FIG. 8.

FIG. 13 is a top view of FIG. 8; and,

FIG. 14 is a bottom view of FIG. 8.
